CYLINDER LOCK

John H. Shaw, New Haven, Conn., assignor to
Sargent & Company, New Haven, Conn.

Application November 10, 1928, Serial No. 318,449

11 Claims. (Cl. 70—47)

My invention relates to a cylinder lock and more especially to a cylinder lock in which the operative parts may be made readily accessible in order to change the combination of the lock, or for other purposes.

It has heretofore been proposed to provide pin tumbler locks in which a lock core is removably secured within a lock housing by key operated means. The usual lock of this character has been provided with pin tumblers having three or more sections, wherein certain of the divisions or breaks in the tumblers are aligned by a key during the normal operation of the lock, and in which other divisions or breaks are aligned by a master or control key when the secondary locking system is to be actuated to bring about the detachment of the lock parts.

In a general aspect, the invention contemplates certain novel features and a novel arrangement of a secondary locking system for detachable locks, without regard to the character of the primary locking system used.

In a more specific aspect, an object of the invention is to provide a lock in which only one set of divisions or breaks in pin tumblers is necessary, and in which the pin tumblers are adjusted by a master key into the same position during the releasing of the lock mechanism for detachment as they are during the normal operation of the lock.

In the secondary locking system of my improved cylinder lock, I propose to provide means which, while inaccessible to an ordinary key, however properly the latter may align the pin tumblers, may be reached by a part of a special or control key to actuate the parts of the secondary locking system to release the several parts of the lock for detachment.

My improved cylinder lock is preferably under the control of a pin tumbler or other lock mechanism, however, and the control key in the preferred form must properly align the pin tumblers or otherwise adjust the primary locking system before the secondary locking system may be actuated.

To these and other ends, the invention consists in the novel features and combination of parts to be hereinafter described and claimed.

In the drawing

Fig. 1 is a general view of a cylinder lock according to my invention;

Fig. 2 is a sectional view of the cylinder lock shown in Fig. 1, but on an enlarged scale;

Fig. 3 is a sectional view, along line 3—3 of

Fig. 2;

Fig. 4 is a perspective view, showing the several parts of the lock detached from one another;

Fig. 5 is a sectional view, along line 5—5 of Fig. 2; and

Fig. 6 is a sectional view, along line 6—6 of Fig. 3.

Referring then to the drawing in which I have illustrated my invention by showing a preferred embodiment thereof, the reference numeral 10 indicates, in general, my improved cylinder lock 10 which comprises an outer shell 11 in which is mounted a key plug housing 12 containing a key plug 13, housing 12 and plug 13 being provided with a plurality of normally aligned cylindrical openings 14 in which are received sectional pin tumblers 15, pin tumblers 15 being urged towards the axis of key plug 13 by means of compression springs 16.

Received within the rear end of shell 11 is a cap or end plate 17 having mounted therein a rotatable collar 18, collar 18 having mounted thereon by suitable means a rollback 19, the particular securing means shown herein comprising screws 20. Collar 18 is slotted at 21, for the reception of a tenon 22 on the end of key plug 13 by means of which rollback 19 may be rotated upon rotation of plug 13. Key plug 13 is provided with the usual opening 23 in which the bit 24 of key 25 may be received, the key 25 being generally of the form disclosed and claimed in my copending Patent No. 1,821,361, granted September 1, 1931, bit 24 being provided with elongated flat notches 26 adapted to align pin tumblers 15, whereupon the key plug and rollback may be rotated.

Key plug housing 12 is secured against movement in one direction in shell 11 by means of end plate 17, the adjacent end of shell 11 being spun over plate 17, as at 27, and in the opposite direction by means of face plate 28 on which are mounted pins 29 and 30 which, when the cylinder lock is assembled, extend through cylindrical openings 29^a and 30^a in shell 11 and engage ring 31, which is normally received in slots 32 and 33 in pins 29 and 30, ring 31 being mounted between shoulder 11^a on shell 11 and the adjacent end of plate 17.

In order that the lock mechanism may be detachable, ring 31 is cut away at 34 and 35 to provide openings which, when brought opposite pins 29 and 30, permit the latter to be withdrawn from shell 11, ring 31 being also provided with an opening 36 in which the end of a master or control key may be received in order to release or lock the secondary locking system. When the

control key is inserted into opening 23, as shown in Fig. 2, the end of the key strikes against ring 31, owing to the fact that opening 36 is not in alignment with opening 23 when the mechanism is locked.

The notches on key 25 align pin tumblers 15 so that the key plug may be rotated by means of key 25. Key plug 13 is rotated until key 25 is opposite opening 36, whereupon the control key 10 may be inserted a further distance into key plug 13, the end of the key entering opening 36. In this position, rotation of key 25 and key plug 13 will produce rotation in ring 31, whereupon the latter may be rotated to bring openings 34 and 15 35 opposite pins 29 and 30, whereupon face plate 28 may be withdrawn from the cylinder lock and the several parts of the lock disassembled.

In order to limit the movement of ring 31 pin 37 is mounted in shell 11, ring 31 being provided 20 with an opening 38 in its periphery in which the pin 37 is received, the ends of the opening cooperating with the pin to limit the movement of the ring.

It will be readily understood that the shell 11 25 is threaded, as at 39, in the usual manner so that it may be used in any usual form of clock case, the usual longitudinally extending slot or slots 40 being provided in which the end of the customary locking screw or screws may be received.

30. From the above description of the nature of my invention and the preferred means for carrying it out, it will be seen that I have provided a relatively simple form of readily detachable lock mechanism in which the usual pin tumbler 35 or other key controlled lock may be used. While I have chosen to described my invention with particular reference to a pin tumbler type of lock, it will be readily understood that the invention may be carried out with other forms of 40 locking mechanisms, and the invention is thus in no way dependent upon the particular type of primary locking mechanism used.

45. While I have shown a preferred embodiment of my invention, it will be understood that it is not to be limited to all the details shown, but is capable of modification and variation within the spirit of the invention and the scope of the appended claims.

What I claim is:

50. 1. In a cylinder lock, a casing, a core in said casing, a face plate, means on said face plate extending through the casing beyond the core, and key controlled means engaging the extending means to releasably secure the face plate to the casing.

60. 2. In a cylinder lock, a casing, a core contained in said casing, a face plate for holding the core in the casing, a pin mounted on the face plate and extending through an opening in the casing, and key controlled means mounted in the casing adapted to engage a pin to secure the face plate to the casing.

65. 3. In a cylinder lock, a casing, a core contained in said casing, and key controlled means for releasably retaining said core in the casing, said means including a face plate, a pin on said face plate extending through the lock casing beyond the core, a slot in the end of said pin, and key operable means mounted in the casing adapted to 70 be received in the slot.

4. In a cylinder lock, a casing, a core contained

in said casing, and key controlled means for releasably retaining said core in the casing, said means including a face plate, a pin on said face plate extending through the casing and beyond the core, a slot in the end of said pin, a ring mounted in said casing and normally received in the slot, said ring being provided with an opening adapted to receive the end of a key inserted through the core and said ring being provided with an opening which may be brought into alignment with the end of the pin upon rotation of the key to release the pin from engagement with the ring. 5

5. In a cylinder lock, a casing, a pin tumbler locking mechanism in said casing, the pin tumblers of said mechanism being provided with a single set of breaks, and key operable means releasably retaining said mechanism within the casing, said key operated means including a rotatable element mounted in the lock casing and engageable by a key inserted in the locking mechanism to be moved into releasing position. 10

6. In a cylinder lock, a casing, a rollback mounted at one end of said casing, a locking mechanism in said casing for operating said rollback, and means carried by the casing for releasably retaining said locking mechanism in said casing, said means including a part engageable by a key inserted in the locking mechanism to be moved into releasing position. 20

7. In a cylinder lock, a casing, a rollback mounted at one end of said casing, a locking mechanism in said casing for operating said rollback, and means carried by the casing and operable by a key inserted in said locking mechanism for releasably retaining said locking mechanism in said casing, said means including a rotatable element mounted in the casing and separable from the locking mechanism. 30

8. In a cylinder lock, a casing, said casing including separable parts, a rollback mounted at one end of said casing, locking mechanism mounted between said parts for operating said rollback, and means carried by said parts and operable by a key inserted in the locking mechanism for releasably securing said parts together. 40

9. In a cylinder lock, a two-part casing, a rollback mounted at one end of said casing, locking mechanism mounted within said casing between said parts for operating said rollback, and rotatable means for locking said parts together, said means being engageable by a key received in the lock mechanism to be rotated into releasing position. 50

10. A door lock unit of cylindrical shape comprising two sections, one of which is adapted to be secured to the door, and a rollback carried by said section, the other of said sections being removably securable to the first section and containing a key operated plug, means for operably connecting the plug to the rollback, and key operated means for securing said sections together. 60

11. A door lock comprising a cylindrical section adapted to be secured to a door and having a rollback movably mounted on the rear end thereof and a forwardly facing chamber, a second section insertable into the chamber and having a key operated plug, means to connect the plug to the rollback, and key operated means for securing the sections together. 70

JOHN H. SHAW.
